(57) **CLAIM**

The ornamental design for a monitor data processing, as shown and described.

DESCRIPTION

1. Monitor data processing

1.1 : Perspective

1.2 : Front

1.3 : Back

1.4 : Left

1.5 : Right

1.6 : Top

1.7 : Bottom

The present ornamental design is a combination of the shape and pattern of a monitor data processing as shown and described; the broken lines indicate unclaimed portions of the article that form no part of the claimed design; the fine parallel and curved lines, shown in all the drawings, indicate the relief of the surfaces of the product.
